UNITED STATES PATENT OFFICE

GEORGE C. BEIDLER, OF ROCHESTER, NEW YORK

PHOTOGRAPHING AND FILM TREATING APPARATUS

Application filed December 19, 1930. Serial No. 503,583.

This invention relates to photographing and developing apparatus and has for an object the provision of mechanism regarded as improvements of an apparatus patented to me on April 3, 1928, No. 1,664,729.

It is a further object of this invention to provide means for operating an apparatus of the character indicated mechanically and to obviate the necessity for the manipulation of certain of the driven means of the apparatus for drawing film from the exposing chamber and delivering it to the developing tank, and for moving film from the developing tank and initially coating the film with a fixing fluid as it is transferred from the developing tank to the receptacle containing the fixing fluid.

It is furthermore an object of this invention to provide novel mechanism whereby a manually operated element which, in the present invention, is intended to operate the cutting device for cutting film after it has been delivered to the developing receptacle, actuates means for establishing a circuit to an electric motor for transmitting power to the several rotary elements of the apparatus and performing other functions which in the patented device were separably manually operated.

It is a still further object of this invention to provide novel means for transmitting power from the motor driven shaft to the gearing by which the film transferring instrumentalities are operated successively and synchronously; the said invention furthermore including means by which the circuit may be established from the source of electricity to mechanisms such as film transfers which may be associated with and form a part of a film treating apparatus intended for developing, fixing, washing and drying film.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, where-

in like characters denote corresponding parts in the several views, and in which—

Figure 1 illustrates a view in elevation of one side of a photographic camera casing showing parts of the invention constituting the controls and such manually operated parts as are located exteriorly of the casing;

Figure 2 illustrates a view in side elevation and partly in section, approximately on the line 2—2 of Figure 1;

Figure 3 illustrates a sectional view of the stop pin on the line 3—3 of Figure 1, with parts associated therewith;

Figure 4 illustrates a view in elevation of the side of the camera structure opposite that shown in Figure 1, with power developing mechanism in elevation;

Figure 5 illustrates a horizontal sectional view of part of the mechanism;

Figure 6 illustrates a view in elevation of the gear wheel and cam shown in Figure 5;

Figure 7 illustrates a view in elevation of a fragment of the apparatus partly in section;

Figure 8 illustrates a sectional view on the line 8—8 of Figure 1;

Figure 9 illustrates a detail view of a ball clutch member;

Figure 10 illustrates a view in elevation of an electric switch employed in the apparatus;

Figure 11 illustrates a plan view thereof;

Figure 12 illustrates a detail view of a crank handle and parts associated therewith;

Figure 13 illustrates an edge elevation thereof;

Figure 14 illustrates a detail perspective view of the upper end of the crank handle;

Figure 15 illustrates an enlarged detail partly in section of a tripping device;

Figure 16 illustrates a sectional view of a part of the device on the line 16—16 of Figure 15;

Figure 17 illustrates a plan view of the film treating mechanism partly in section; and

Figure 18 illustrates a detail view of a fragment of an operating crank and a dog associated therewith.

In these drawings, 20 denotes an exposing chamber of known type, which is associated

with a bellows 21 of a light projecting means common in this art and which need not be illustrated more in detail. The casing 20 which contains the exposing chamber is provided with rollers 22 and 23 which are rotated, as will presently appear, for drawing film from the exposing chamber, causing it to travel into a receptacle 24 for developing fluid where, in the present showing, the film will be guided by the coil 25, arranged in the receptacle. This feature of the developing tank and coil form the subject of patents to me, one of which is dated July 13, 1920, and numbered 1,346,780 and need not, it is thought, be described in detail.

An element 26 is movable in guides such as 26^a in a plane above the receptacle 24 and preferably this element constitutes a cover for the receptacle 24 in order that the said cover will prevent evaporation and deterioration of the developing fluid. Arms 27, preferably resilient, have their ends anchored to the member 26 and project from the front edge thereof a suitable distance to assume positions with respect to other mechanisms, which will be presently explained. A roller 28 is rotatively mounted to be supported by the resilient arms and in position slightly below knives 29 and 30, between which the film is fed into the receptacle 24 so that after the film has been so feed, it may be cut by the knives 29 and 30, such as is well known in the art.

In proximity to the knives, but on the side thereof opposite that occupied by the developer receptacle 24, a roller 31 is mounted to cooperate with the roller 28 when the member 26 is moved to carry the roller 28 under the knives 29 and 30. When such movement occurs, film that has been delivered to the developing receptacle 24 will have its upper edge in the path of travel of the roller 28 and the roller 28 will therefore flex the projecting upper edge of the film and press it against the roller 31. The relation of parts is such that the axis of the roller 28 will pass the axis of the roller 31 by riding over the periphery of the roller 31 with the film interposed between the two rollers. By reason of the arrangement of parts just described, the film will be flexed or bent downwardly to a degree over the roller 31 in order that when the said roller 31 is turned, as will be presently explained, the film will be drawn from the developing receptacle 24 and moved downwardly on an incline to the receptacle 32 for the fixing fluid, but it is the purpose of the inventor that prior to the delivery of the film to the fixing fluid, it shall be provided with an initial coating of fixing fluid in order that the developing of the film will be arrested and prevented from being affected by light during its subsequent treatment which is intended to fully fix the film prior to its being washed.

In moving film from the developing receptacle 24, it will, of course, be drawn from the coil in a direction reverse to that which it traveled when entering the receptacle and as the roller 31 is rotated the pressure of the roller 28 on the film will be sufficient to produce friction which will cause the film to be moved. In order that the film may be properly directed from the roller 31 to the location where it receives its initial coating, a film guiding and transfer device is interposed between the roller 31 and the fixing fluid receptacle 32. The film transfer may be of any appropriate construction and it may consist of two end plates such as 33 and an inclined plate such as 47 and associated parts, as will presently appear, and the film transfer is preferably removably applied to the tray 32 which is intended to contain fixing fluid.

The film transfer further includes supporting elements on which the film travels in its descent from the roller 31 to a location where the film is initially coated with fixing fluid. The supporting elements are preferably relatively narrow ribs or fins 37 which lie in an inclined position on the plate 47. The ribs serve to support the film in a manner to minimize friction as the film travels over the ribs and permits the film to move without causing any rub or marks which affect the coated surface of the film, and this is of particular importance when double coated film is being treated. The upper edges of the ribs near their ends are concave, and at or near their ends the upper edges of the ribs are convex; hence, film will be guided into the depression caused by the concavities of the ribs and then elevated when the film travels over the said convex surfaces of the ribs. It has been found in practice that when the guiding members or ribs 37 are of the configuration illustrated in the drawings, the film will be caused to dip into the fixing fluid and then will pass out of the fixing fluid over the ends of the guides and be delivered in the receptacle 32 on top of fixing fluid.

As a means for causing the film to travel from the ribs of the frame, a drum 38 is rotatively mounted in the frame so that its periphery above the axis is about alined with the upper edges of the ribs, and friction wheels 39 preferably having rubber tires or peripheries coact with the drum 38 and hold the film on the drum 38 in order that the motion of the friction wheels will be imparted to the film to draw it through the fixing fluid and eject it therefrom. The friction wheels are mounted on a shaft 40, which shaft is also supplied with a gear wheel 41 meshing with a pinion 42 on the shaft 43. The shafts 40 and 43, as well as trunnions of the drum, are rotative in a standard or bracket 45 at one end of the frame, whereas the shaft 40 and the trunnion of the drum at the end opposite the standard 45 are journaled in a similar

standard (not shown) at the opposite end of the frame. The transfer as described is the subject in part of a patent to me No. 1,714,841 of May 29, 1929.

5 The ribs 37 have their bases secured to the inclined plate 47, a part of the frame structure, and the free lower ends of the ribs which project outwardly from the plate 47 have a brace 47^a attached to them in order that the 10 structure will be made more rigid. A gear wheel 48 is secured on the shaft 43 and it is intended to be driven by mechanism, to be presently explained, with relation to which the frame and the parts mounted thereon, as 15 just described, are removable.

The cause for making the frame and the parts mounted thereon removable is to facilitate access to the interior of the apparatus, cleaning of the fixing fluid receptacle, and 20 for other purposes.

The reciprocating member 26 is held normally retracted with respect to the roller 31 and the feed rollers which draw film from the exposing chamber, and to accomplish the result 25 in the present embodiment of the invention the member 26 has an abutment or depending portion 49 engaged by a plunger rod 50 which is under pressure of a spring 51. The spring is assembled to encircle a portion 30 of the plunger rod and the plunger rod projects through the end of a cylinder 52. The spring is also located in the cylinder and engages a shoulder 53 of the plunger rod so that, as stated, the member 26 will be forced 35 rearwardly by the action of the spring.

Mechanism is provided for moving the member 26 in the opposite direction to that imparted to it by the spring after film has been delivered to the developing receptacle 40 and after it has been severed, and to accomplish the said result a rock shaft 54 is journaled in the casing and it is provided with arms 55 that extend upwardly into engagement with the flange or abutment 49 and as 45 the rock shaft moves in one direction the arms will exert pressure on the member 26 to overcome the pressure of the spring and to impart movement to the member 26 in order that it will carry the roller 28 and cause it 50 to flex the upper end of the cut film and force the said film over and in firm contact with the roller 31, from which it will be delivered to the device by which it is transferred to the fixing fluid. The rock shaft is provided with 55 a shaft operating arm 56 near its end within the case, and a bar 57, which may be termed a thrust bar, has one end pivotally connected to the arm 56, whereas its opposite end is provided with mechanism which, coacting with other parts of the device, will serve to forcibly move the bar, as will presently appear.

The inner face of the bar near the end remote from the rock shaft has a longitudinally extending rib 58 which is engaged by a spring 65 60 that serves to press the bar toward the

inner wall of the case, and the said end of the bar remote from the rock shaft, which will hereafter be referred to as the outer end, has a bearing plate or extension 60 lying parallel with the outer face of the bar and it projects but a slight distance from the outer end. The bearing plate or extension is integral with or attached to the outer end of the bar and it with the bar constitutes a support for a stud or trunnion 61 of a wheel 62, but there is a clearance between the inner side of the wheel and the outer surface of the bar which is equal to or greater than the width of the cam 63 which is intended to coact with the wheel when the parts are in a certain position and to rotate independently of the wheel when the parts are in another position.

A hollow shaft 64 projects into the casing and a gear wheel 67 is rotatively mounted on it. The gear wheel has a hub 68 and the cam 63 is rigid with respect to and is carried by the hub. The shaft 64 is associated with a face plate 65 which is secured on the outer surface of the casing and the said plate has a hollow boss 66 provided with internal threads 66^a that are engaged by a threaded element 66^b having a thrust pin 66^c which it carries, the said thrust pin projecting through the hollow shaft and being movable axially therein. The threaded element 66^b is partially rotated, as will presently appear, to project and retract the thrust pin.

The outer face of the bar 57 has a longitudinally extending way or guide 71 in which the inner end of the thrust pin extends so that as the rod reciprocates, as will presently appear, the bar will be held in operative relation to the mechanism with which it is associated. Normally, when the bar lies against the side of the cam, or approximately so, and the parts are in the position shown in Figure 5, the wheel 62 is out of alinement with the cam 63, but if the threaded element is rotated clockwise, the thrust pin will be projected inwardly, and as it moves inwardly, it will impart movement to the bar, forcing it against the action of the spring 59 until the wheel 62 is caused to aline with the cam. When the thrust pin has been moved inwardly, it will cause the thrust bar to carry the wheel 62 into alinement with the cam 63 and as the wheel 67 is driven, it will rotate the cam which will be carried around into engagement with the wheel 62 and further rotation of the wheel 67 will cause the cam to force the bar longitudinally, and such movement will, of course, operate the rock shaft through the connections heretofore described. The bar has an aperture 72 intended to aline with the inner end of the thrust pin 66^c and when the aperture alines with the thrust pin, the spring 59 will force the bar laterally so that the end of the thrust pin will lie in the aperture 72 and permit the wheel 62 to be carried out of alinement with the cam 63. The bar

130

will be held for retaining parts of the mechanism, and the gear wheel 67 may be freely rotated to operate parts of the mechanism, as will hereafter appear.

It was stated that the gear wheel 48 was to be driven by mechanism to be explained and, in the present embodiment of the invention, when the frame is installed in the case, the gear wheel 48 overlies the gear wheel 67 and meshes with it, so that when the wheel 67 is rotated the film moving mechanism of the frame or transfer is actuated.

An idle wheel 74 is rotative with a shaft 75 and the said wheel meshes with the gear wheel 67 and a gear wheel 76 which is likewise rotative on a stud or shaft inside of the case.

The roller 31 is preferably rubber jacketed or otherwise provided with means to increase its gripping action on the film to be moved and when it is rotated after the roller 28 has carried the film into engagement with it and pressed the film on it, the film will be drawn from the developing receptacle and, of course, down the ribs, from which it will be taken by the wheels and the drum. One end of a shaft or trunnion of the roller 31 is provided with a pinion 77 that meshes with the wheel 76 so that through the gearing the roller 31 and the friction wheels 39 are operated in unison when power is applied, as will be presently explained. It is the purpose of the inventor to so proportion the gearing that the film will be drawn from the developing receptacle while being delivered to the transfer and ejected from the transfer by means that will impart uniform movement to the film.

It might be stated that the knife 29 is reciprocated through the use of racks 29^a operated by gear wheels 29^b. The gear wheels 29^b are on a shaft 78 and the shaft is partially rotated in opposite directions by a crank 79. The shaft 78 extends through the casing and projects on the opposite side thereof and it carries a wheel 80 having a contact plate 81 which is a conductor of electricity. Contact brushes 82 and 83 are electrically connected when the wheel 80 is rotated to bring the contact plate into engagement with the said brushes, and the terminals of the brushes have conductors 84 and 85, respectively, which are connected to a source of electricity and a motor 86, respectively, so that when the cutting mechanism is operated to a predetermined degree the motor is energized, and through a power transmitting means 87 the shaft 88 extending partially through the casing is driven. Another set of brushes A, similar to the contact brushes 82 and 83, is intended for furnishing current to control mechanisms associated with the photographing and developing apparatus, such devices being means for transferring film with relation to fluid tanks such as are used for washing prints and otherwise treating them.

The shaft 88 is provided with a sprocket wheel 89 engaged by a chain 90 operating over a sprocket wheel 91 on the shaft 75. Power is applied by this means for rotating the shaft 75 and the gear wheel 74 thereon which, as has been stated, is in mesh with wheels 67 and 76 so that they will be driven to operate the film transferring means. The crank 79 is associated with a plate 92 mounted on a pivot 93 and the said plate extends into engagement with the handle 94 of the crank and the handle is movable axially of the trunnion 95 on which the handle rotates. The plate and the said handle are under the influence of a spring 96 which holds the handle normally toward the outer end of the trunnion 95, and the plate has a lug 97 which moves at the edge of the crank as the handle is pushed in by hand or retracted by the spring 96. As the crank 79 is manually operated to partially rotate the shaft 78 and when it has been moved a certain distance, the said crank encounters a stop pin 98 which is movable in a tubular bracket 99, the said stop pin being held normally projected by a spring 100, but its outward movement is limited by reason of the presence of a pin 101 which moves in a slot 102, the said pin abutting the other end of the slot for the purpose of limiting its motion. When the crank is in engagement with the side of the pin, the edge of the lug 97 is in alignment with the end of the pin and when the handle is pressed inwardly, the stop pin is pressed inwardly beyond the inner surface of the crank and the crank is then free to move further in the direction of its initial movement, as shown by the arrow, Figure 1. The crank is provided with a camming surface 103 which engages the pin on the return movement of the said crank and presses the said pin out of the path of travel of the crank during this part of the operation. The inner face of the crank is also provided with a bracket 104 in which a roller 105 is mounted.

The shaft 22^a of the feed roller 22 is extended to the exterior of the casing and a clutch element 106 is splined thereon. The outer end of the shaft 22^a is supported by a bracket 107 having a bearing 108, and a sprocket 109 is rotative on the shaft and its hub is formed as a coacting clutch member 110 with relation to which the clutch member 106 operates. The shaft 75 that extends through the casing is rotative in a bearing 111 on the lower end of the bracket 107. The shaft 75 has a sprocket wheel 112 engaged by the sprocket chain 113 which rotates the wheel 109 so that when the clutch members 106 and 110 are in engagement the feed roller 22 is operated. The sprocket wheel 112 is not itself attached to the shaft 75 but there is interposed between the said shaft and the said sprocket wheel a sleeve 114 forming one element of a clutch, which sleeve is secured to

the shaft in any appropriate way, as by a pin 115. The sleeve has ball seats 116, the inner surfaces of which are tapered and balls 117 located in radial channels 118 formed in an annular flange 119 on the hub of the sprocket wheel 112 are forced into the ball seats 116 by the springs 120, it being shown that the springs are engaged by screws 121 threaded in the outer ends of the channels in which the balls and springs are assembled. The provision of a clutch of this character is desirable in order to absorb shock due to the sudden interruption of motion of one part with relation to the other as the balls may be forced out of the operative relation which they occupy when the parts are being driven.

As a means for operating the splined clutch member, a lever 122 is oscillative on a pivot 123 and it has a lower forked end projecting 20 into an annular slot 124 of the splined clutch member. The upper end of the lever is in the path of travel of the roller 105. Therefore, when the crank has been moved past the stop pin, the roller will force the upper end of the 25 lever inwardly and cause the clutch members to engage in order that power may be transmitted to the feed roller for drawing film from the exposing chamber and delivering it to the developing instrumentalities.

30 The motion of the crank is also utilized for imparting rotary motion to the threaded element 66^a. A crank 125 is secured on the outer end of the threaded element and the said crank operates in a slot 126 formed in the 35 lower end of a rock arm 127 which is pivoted on a stud 128 of a bracket 129. The rock arm is normally under the tension of a spring 130 which is operative to rotate the threaded element in a direction counter to that in which 40 it is moved by the crank.

In order to operate the rock arm by the movement of the crank, the lower end of the crank is provided with a spring-pressed dog 45 whose movement is limited in one direction by a pin 132. When the crank is moved in the direction of the arrow shown in Figure 1, the dog engaging the rock arm moves the said rock arm on its pivot and this in turn rotates the threaded element 66^b. After this 50 movement has been imparted to the rock arm to a certain degree, the lower end of the dog passes beyond the upper end of the rock arm and hence the rock arm is released and is free to be returned to its former position by the 55 said spring 130, and on the return movement of the crank the dog cams over the upper surface of the rock arm and the parts are restored to their positions for a repetition of the operation.

60 Assuming that a print is in the developing tank and has had its proper developing time, the lever 79 is moved in the direction of the arrow in Figure 1 until it engages the stop pin 98. This movement causes the small 65 crank 125 to partially rotate through the lever

127, pushing thrust pin 66^c in bringing cam 63 into action, causing rod 57 to move forward, bringing roller 28 in contact with roller 31, which causes the rollers to eject the print from the developing coil and tank. The knob 70 75 94 is then pressed to permit the arm 79 to pass the pin 98, which causes the dog 131 to ride over the lever 127 which then returns to its original position, and at the same time bringing roller 105 in contact with clutch lever 122, thereby causing another sheet of paper to be wound down into the developing coil. When a sufficient number of revolutions has been 80 made to feed the correct amount of paper in the coil, the ball clutch, Figures 8 and 9, releases and the lever 79 is immediately pulled in a direction opposite that shown by the arrow, which movement actuates the knife and severs the paper. It will be observed that when the lever 79 is in contact with the pin 98, the metal strip 81, Figure 10, will be in contact with the brushes 82 and 83, Figure 11, and when in this position the motor is energized, operating the machine. This metal strip 81 remains in contact with brushes 82 85 90 and 83 during the movement of the lever 79 from pin 98 to clutch lever 122, thereby causing the motor to continue running which it does until the lever 79 reaches the vertical position, and when the further movement of the lever is made opposite the direction of the arrow, which is necessary to sever the paper, the metal strip 81 comes in contact with the brushes A, Figure 10, thereby energizing the solenoid magnets for operating the transfer. 95 100

I claim:

1. In a photographic apparatus, means for drawing film including a clutch member, a driven clutch member associated with the first mentioned clutch member, a cutter for the film, means for operating the cutter, and means operated by the cutter-operating means for effecting the engagement of the afore- 105 said clutch members.

2. In a photographic apparatus, means for drawing film including a clutch member, a clutch member associated with the first mentioned clutch member, a motor for driving the clutch member, a cutter for the film, means for operating the cutter, means operated by the cutter-operating means for effecting the engagement of the aforesaid clutch members, and means associated with the cutter-operating means for causing the 110 115 120 operation of the motor.

3. In a photographing and film treating apparatus, means containing a supply of film, means for drawing film therefrom and delivering it to a receptacle, including a clutch member, a driven clutch member coacting with the first mentioned clutch member, a cutter for cutting film after it is delivered to the receptacle, means for moving film from the receptacle, gearing for operating one of the clutch members and the film moving 125 130

means, a motor operative to drive the gearing, a device for operating the cutting means to effect engagement of the clutch members and means moved by the device for operating the cutter controlling the operation of the motor.

4. In a photographing and film treating apparatus, means for containing a supply of film, means for drawing film therefrom and delivering it to a receptacle, including a clutch member, a driven clutch member coacting with the first mentioned clutch member, a film transfer means for moving film from the receptacle and delivering it to the transfer, means for operating the transfer, gearing for operating one of the clutch members, the film moving means and the transfer, a motor operative to drive the gearing, a cutter for film located between the film supply and the receptacle, means for operating the cutter, means operated by the last mentioned means for coupling the clutch members together, means by which the operation of the cutter causes the operation of the motor, and means operated with the cutter for coupling the gearing to the film moving means.

5. In a photographing and film treating apparatus, means for containing film, means for drawing film therefrom and delivering it to a receptacle, a cutter for film, means for moving film from the receptacle, gearing for driving the last mentioned means, a motor having means for driving the gearing, means for operating the cutter, and means associated with the last mentioned means for controlling power for the motor.

6. In a photographing and film treating apparatus, means for containing film, means for drawing film therefrom and delivering it to a receptacle, a cutter for film, means for moving film from the receptacle, gearing for driving the last mentioned means, a motor having means for driving the gearing, a crank for operating the cutter, a thrust pin for actuating parts of the mechanism, and means actuated by the crank for projecting and retracting the thrust pin.

7. In a photographing and film treating apparatus, means for containing film, means for drawing film therefrom and delivering it to a receptacle, a cutter for film, means for moving film from the receptacle, gearing for driving the last mentioned means, an electric motor having means for driving the gearing, a crank for operating the cutter, and means associated with the crank for controlling current for the motor.

8. In a photographing and film treating apparatus, means for containing film, means for drawing film therefrom and delivering it to a receptacle, a cutter for film, means for moving film from the receptacle, gearing for driving the last mentioned means, a motor having means for driving the gearing, a crank for operating the cutter, a stop pin for the crank, manually operated means on the crank

for dislodging the stop pin from the path of travel of the crank, means for returning the pin to its first mentioned position, and means on the crank for automatically moving the pin out of the path of the crank on its return movement.

9. In a photographing and film treating apparatus, means for containing film, means for drawing film therefrom and delivering it to a receptacle, a cutter for the film, driven means for moving the film from the receptacle, a rotative element coacting with the last mentioned means, means for shifting the position of the rotative element including a reciprocating bar, means for moving the bar longitudinally, a thrust pin for moving the bar laterally into operative relation with its moving means, gearing for driving the said moving means, a motor having means for driving the gearing, a crank for operating the cutter, means whereby the movement of the crank shifts the thrust pin, and means for energizing the motor.

10. In a photographing and film treating apparatus, means for containing film, means for drawing film therefrom and delivering it to a receptacle, a cutter for the film, driven means for moving the film from the receptacle, a rotative element coacting with the last mentioned means, means for shifting the position of the rotative element including a reciprocating bar, means for moving the bar longitudinally, a thrust pin for moving the bar laterally into operative relation with its moving means, means for shifting the bar laterally against the action of the thrust pin, gearing for driving the said moving means, a motor having means for driving the gearing, a crank for operating the cutter, means whereby the movement of the crank shifts the thrust pin, and means for energizing the motor.

11. In a photographing and film treating apparatus, means for containing film, means for drawing film therefrom including a clutch member, means for cutting the film, a crank for operating the means for cutting, a driven clutch member adapted to coact with the other clutch member, one of which is movable with relation to the other, a member carried by the crank, a member operative to shift the movable clutch member actuated by the member carried by the crank, and instrumentalities for restoring the parts to normal positions.

12. In a photographing and film treating apparatus, means for containing film, means for drawing film therefrom and delivering it to a receptacle, a cutter for the film, means for moving film from the receptacle including coacting rollers, a shiftable member carrying one of the coacting rollers, a longitudinally movable bar operative to move the shiftable member in one direction, means for moving the shiftable member in the opposite

- direction, a rotatively mounted cam, a cam engaging element on the bar, means for moving the bar in one direction, whereby the cam and cam engaging element are inoperative, a thrust pin engaging the bar to move said bar for operatively positioning the cam and cam engaging element, a crank for operating the cutter, means whereby the crank projects and retracts the thrust pin, gearing for driving the means for moving the film from the receptacle, a motor, means driven by the motor for driving the gearing, and means actuated by the crank for controlling the motor. 5 70
- 10 13. In a photographing and film treating apparatus, means for containing film, means for drawing film therefrom and delivering it to a receptacle, a cutter for the film, means for moving film from the receptacle including coacting rollers, a shiftable member carrying one of the coacting rollers, a longitudinally movable bar operative to move the shiftable member in one direction, means for moving the shiftable member in the opposite direction, a rotatively mounted cam, a cam engaging element on the bar, means for moving the bar in one direction, whereby the cam and cam engaging element are inoperative, a thrust pin engaging the bar, threaded elements one of which is rigid with the thrust pin and the other of which is stationary, a crank for operating the cutter, means associated with the crank for partially rotating the thrust pin, whereby the threaded elements associated with it move said thrust pin axially into engagement with the bar for moving it laterally, whereby the cam engaging element is operatively positioned with relation to the cam, gearing for driving the means for moving the film from the receptacle and operating the cam, a motor, means driven by the motor for driving the gearing, and means for controlling power for the motor. 20 80
- 25 14. In a photographing and film treating apparatus, means for containing film, means for drawing film therefrom and delivering it to a receptacle, a cutter for the film, means for moving film from the receptacle including coacting rollers, a shiftable member carrying one of the coacting rollers, a longitudinally movable bar operative to move the shiftable member in one direction, means for moving the shiftable member in the opposite direction, a rotatively mounted cam, a cam engaging element on the bar, means for moving the bar in one direction, whereby the cam and cam engaging element are inoperative, a thrust pin engaging the bar to move said bar for operatively positioning the cam and cam engaging element, a crank for operating the cutter, means whereby the crank projects and retracts the thrust pin, gearing for driving the means for moving the film from the receptacle, an electric motor, contacts one of which is connected to a source of electricity and the other to the motor, a switch having a conductor plate movable with relation to the contacts for conducting electricity from one contact to the other, means operated by the crank for moving the switch, and means driven by the motor for driving the gearing. 30 90
- 35 15. In a photographing and film treating apparatus, means for containing film, means for drawing film therefrom and delivering it to a receptacle, a cutter for the film, means for moving film from the receptacle including coacting rollers, a shiftable member carrying one of the coacting rollers, a longitudinally movable bar operative to move the shiftable member in one direction, means for moving the shiftable member in the opposite direction, a rotatively mounted cam, a cam engaging element on the bar, means for moving the bar in one direction, whereby the cam and cam engaging element are inoperative, a thrust pin engaging the bar to move said bar for operatively positioning the cam and cam engaging element, a crank for operating the cutter, means whereby the crank projects and retracts the thrust pin, gearing for driving the means for moving the film from the receptacle, an electric motor, contacts one of which is connected to a source of electricity and the other to the motor, a switch having a conductor plate movable with relation to the contacts for conducting electricity from one contact to the other, means operated by the crank for moving the switch, and means driven by the motor for driving the gearing. 40 100
- 45 16. In a photographing and film treating apparatus, means for containing film, means for drawing film therefrom and delivering it to a receptacle, a cutter for the film, means for moving film from the receptacle including coacting rollers, a shiftable member carrying one of the coacting rollers, a longitudinally movable bar operative to move the shiftable member in one direction, means for moving the shiftable member in the opposite direction, a rotatively mounted cam, a cam engaging element on the bar, means for moving the bar in one direction, whereby the cam and cam engaging element are inoperative, a thrust pin engaging the bar to move said bar for operatively positioning the cam and cam engaging element, a crank for operating the cutter, means whereby the crank projects and retracts the thrust pin, gearing for driving the means for moving the film from the receptacle, an electric motor, contacts one of which is connected to a source of electricity and the other to the motor, other contacts one of which is connected to a source of electricity and the other to a terminal of an electromagnetic control of coacting instrumentalities, a switch having a conductor plate adapted to selectively engage either set of contacts, and means actuated by the crank for carrying the switch. 50 110

17. In a photographing and developing apparatus, a casing for containing a web of film, a receptacle for developing fluid therein, means for delivering film thereto, means for severing the film above the receptacle from a web of film from which the film in the receptacle is delivered, a slidably mounted cover for the receptacle, a rotative element on one side of the projecting portion of the film, a rotative element adapted to contact therewith, supports for the second mentioned rotative element carried by the cover of the receptacle, means for imparting motion to the cover in one direction, means for imparting motion to the cover in another direction, comprising a rock shaft, a film transfer, arms secured on the rock shaft and engaging the end of the cover, a reciprocating bar connected to the rock shaft for partially rotating the same, a hollow shaft extending inwardly from the casing at right angles to the axis of the bar, a thrust pin slidable in the hollow shaft, a wheel rotative on the hollow shaft, a cam rotative with the wheel, an abutment carried by the bar and spaced from the side of the bar, means for holding the bar in operative relation to the thrust pin and in proximity to the side of the cam when the parts are in position with the abutment out of alinement with the cam, means for moving the thrust pin axially for displacing the bar and carrying the abutment into alinement with the cam, whereby rotation of the cam will move the bar longitudinally, the said bar having an aperture which receives the extended end of the thrust pin, whereby the means for holding the bar in operative relation with the shaft forces the bar laterally and the abutment is carried out of alinement with the cam, gearing operated by the gear wheel for actuating the film drawing device and the transfer, a motor for driving the said gearing, means for operating the film severing means, and devices actuated thereby for operating the thrust pin, controlling the operation of the motor, and driving the film moving means and the film drawing means.
18. In a photographing and film treating apparatus, means for containing film, means for drawing film therefrom and delivering it to a receptacle including a clutch member, a driven clutch member coacting with the first mentioned clutch member, means for moving film from the receptacle, gearing for operating one of the clutch members and the film moving means, a motor operative to drive the gearing, and means for controlling the operation of the motor.
19. In a photographing and film treating apparatus, means for containing a supply of film, means for drawing film therefrom and delivering it to a receptacle including a clutch member, a driven clutch member coacting with the first mentioned clutch member, means for moving the film from the

receptacle, gearing for operating one of the clutch members and the film moving means, means for moving the clutch members into inoperative and cooperative relation with each other, a motor operative to drive the gearing, and means for controlling power for the motor.

20. In a photographing and film treating apparatus, means for containing film, means for drawing film therefrom and delivering it to a receptacle, means for moving film from the receptacle including coacting rollers, a shiftable member carrying one of the coacting rollers, a longitudinally movable bar operative to move the shiftable member in one direction, means for moving the shiftable member in the opposite direction, a rotatively mounted cam, a cam engaging element on the bar, means for moving the bar in one direction whereby the cam and cam engaging element are inoperative, a thrust pin engaging the bar to move said bar for operatively positioning the cam and cam engaging element, means for projecting and retracting the thrust pin, gearing for driving the means for moving the film from the receptacle, a motor for driving the gearing, and means for controlling power for operating the motor.
